UNITED STATES PATENT OFFICE

WILLIAM J. DE WITT, OF AUBURN, NEW YORK, ASSIGNOR TO SHOE FORM CO. INC., OF AUBURN, NEW YORK, A CORPORATION OF NEW YORK

EXPANSIBLE TOE FORM

Application filed December 20, 1928. Serial No. 327,399.

This invention relates to an expandable toe form adapted to keep the toe of footwear plumped out or free from wrinkles and is an improvement upon the shoe form disclosed in my Patent No. 1,646,016 dated October 18, 1927 differing therefrom in certain details of construction.

The primary object of this invention is to provide a form which, due to the inherent functions of its component elements, normally expands into the functioning position and which will easily collapse from such position in order to permit the insertion or withdrawal of the form.

A further object of this invention is to provide a toe form comprising a shell of resilient material the walls of which are connected by a normally resilient cross brace which will supplement the natural resiliency of the material and cause the form to expand into its normal position while permitting it to contract under pressure.

Other objects of this invention will appear from a consideration of the following specification taken in connection with the drawings, in which:

Fig. 1 is a bottom plan view of a toe form embodying one modification of this invention;

Fig. 2 is a similar view of a form embodying another modification of this invention;

Fig. 3 is a bottom plan view of a third modification of the invention; and

Figs. 4 and 5 are views in elevation of cross braces that might be employed in place of the cross braces disclosed in Figs. 1 and 2.

The toe form is designated generally in the drawings by the reference numeral 10 and is made of thin resilient material shaped into a hollow member or shell having side walls 11 and 12 which terminate in flanges 13 and 14.

The flanges which may be integrally connected at the toe, as shown in the drawings, are preferably in the same plane so that

they rest upon the inner sole of a shoe when the form is positioned in the toe thereof.

The walls 11 and 12 of the form, due to the resiliency of the material, tend to expand and, when inserted in the toe of a shoe, to fill out the toe by holding the material thereof smooth and free from wrinkles. By reason of the difference in materials employed in shoes the resistance to this action varies and in order to insure the plumping of the shoe material the tendency of the form material is supplemented by cross braces or similar means which are normally resilient. Thus in the modification shown in Fig. 1, the walls 11 and 12 are provided with a cross piece or brace 15 of integral spring wire having a loop 16 intermediate its ends. Preferably this brace is secured to the flanges 13 and 14 by rivets 17 and 18. The ends 20 of the brace are bent to surround the shanks of the rivets 17 and 18 in order to allow a certain amount of pivotal movement of the brace relative to the rivets. The brace, being, as pointed out above, of spring wire and having the loop 16, normally tends to take the position shown in Fig. 1 and thus to supplement the normal expansive elasticity of the walls.

When pushed into the toe of the shoe the form may be grasped at its rear edges and the cross brace 15 contracted a trifle. The walls of the shoe limit the expansion of the form so that when it reaches the final position the side walls of the form plump out the toe. The shoe walls alone may be relied upon to contract the brace but it has been found that a preliminary contraction, while not necessary, facilitates the operation. The legs 19 of the brace 15 incline forwardly from the loop 16 so that the angle of the loop may be said to open toward the toe; hence the brace 15 may easily be contracted solely by the walls of the shoe when the form is withdrawn.

The modification shown in Fig. 2 is similar to that shown in Fig. 1 and comprises the same elements. The brace 15^a however is in

the reverse position to that which it occupies in Fig. 1; that is to say, the angle of the loop 16^a opens toward the heel instead of toward the toe. By reason of this construction, when the form is inserted into the shoe, the brace 15^a will contract more easily due to the contact of the side walls of the form with the walls of the shoe than in the first modification and the form can be quickly and easily slid into the proper position, in which position the brace will expand to the limit set by the shoe and plump out the toe. When the form is to be withdrawn from the shoe, the back edges of the form may be grasped and the side walls contracted so that it can be extracted.

Fig. 3 is similar to Fig. 1 with the exception that there is provided a back part wire or thrust bar 21 which engages the front member of the loop 16. The thrust bar facilitates the extraction of the form from the toe of the shoe because, by pulling on the bar, the brace is positively contracted thus separating the side walls of the form from the shoe walls. The form may be slid into the shoe in the manner described and the rear end of the bar braced against the heel counter of the shoe in the well known manner, such as is shown in the patent above mentioned. In that case the resiliency of the thrust bar will supplement the action of the brace 15 and further insure full contact of the side walls with the shoe walls. It will be noted that the loop 22 of the thrust bar encircles the forward portion of the loop 16 and that the thrust bar is above the rear portion of such loop. Hence the pivotal movement of the toe form on the thrust bar will be limited, all as pointed out in my copending application filed on even date herewith.

Figs. 4 and 5 illustrate other forms of cross pieces or braces that might be employed in place of the ones heretofore described. Thus in Fig. 4 the brace 25 is made almost right angular in shape with a central loop 26 and looped ends 27. In Fig. 5, the brace 30 is made substantially W-shaped in form, having outer legs 31 and 32, inner legs 33 and 34, the legs 31 and 33, 32 and 34 being connected by loops 35 while the legs 33 and 34 are connected by a loop 36. As pointed out above, either of these constructions might be substituted for the constructions shown in either Figs. 1 or 2 and when so placed will function in the manner of the braces 15 in those figures.

While certain embodiments of the broad invention have been shown and described I am not limited thereto since other embodiments might be made without departing from the spirit and scope of the invention as set forth in the following claims.

I claim:

1. In a shoe form comprising a shell having flanges at the bottoms of its side walls, a single normally resilient brace connecting

said flanges, said brace being provided with a loop intermediate its ends, and a thrust bar pivotally secured to said loop.

2. In a shoe form comprising a shell having flanges at the bottoms of its side walls, a single normally resilient brace connecting said flanges, said brace being pivotally connected at its ends to the flanges and being provided with a loop intermediate its ends, and a thrust bar pivotally secured to said loop.

Signed by me at Auburn, New York, this 18th day of December, 1928.

WILLIAM J. DE WITT.
